UNITED STATES PATENT OFFICE.

ALFRED NEWHOPE, OF SAN FRANCISCO, CALIFORNIA, ASSIGNOR TO UNDERWOOD TYPEWRITER COMPANY, OF NEW YORK, N. Y., A CORPORATION OF DELAWARE.

TYPEWRITING MACHINE.

Application filed September 29, 1925. Serial No. 59,258.

This invention relates to sound-deadening means for typewriting machines, and more particularly to sound-subduing cases which enclose the lower portions of typewriting machines without affecting their operations.

A feature of the invention is the provision of a pliable sound-retarding bag for partially enclosing a typewriting machine 10 from below, without interfering with its operation, which can be inexpensively manufactured, and easily applied to a machine after it has left the factory, and the use of which will not require additional space.

Another feature is the provision of a pliable sound-absorbing material adapted for use in the construction of sound-retarding bags for typewriting machines.

According to the present invention, an open bag is provided which is arranged for neatly enclosing the lower portion of a typewriting machine which rests upon the bottom of the bag. The walls of the bag may extend upwardly to engage snugly against 25 and be substantially flush with the top of the keyboard-frame at the front, and with the top frame-members at the sides. The rear wall of the bag may extend upwardly to the way-rod-supporting frame-members. Relatively stiff framing strips may be fastened outside along the top edges of the bag on the front and sides, and an adjustable strap means may be provided at the rear for connecting the side strips and holding the same closely against the typewriting frame.

The pliable material from which the bag is made may be formed in layers. The outer layer will preferably consist of substantially air-tight, wear-resisting material, while the inner layers may be alternating layers of sound-absorbing felt and loosely-woven fabric, a layer of the latter having poor sound-reflecting properties being placed 45 next to the machine.

One of the features of the invention is the arrangement of the walls of the bag with an outward bulge to prevent the walls touching any metal parts of the typewriting machine except along their top edges.

Another feature is the arrangement of the back wall of the bag of a length slightly greater than the width of the machine, whereby the side walls may be spread apart

to permit easier insertion of the machine 55 into the bag.

Other features and advantages will hereinafter appear.

In the accompanying drawings,

Figure 1 is a perspective view of the 60 sound-deadening bag in place on an Underwood typewriting machine, the latter being indicated by a phantom view in dash-and-dot outlines of portions of the frame, and certain other principal parts. A small portion of the bag is shown broken away at the front to illustrate its layer construction.

Figure 2 is a rear end view of the same.

Figure 3 shows a cross-sectional view of 70 the bag with an exaggerated outward bulge in the front and back walls. An Underwood typewriter is indicated as being lowered to position for fastening the bag to the machine.

Figure 4 is an enlarged fragmentary section through the bottom of the bag for illustrating its layer construction.

In carrying out the invention, provision is made of an open bag 10, constructed of a pliable material hereinafter described. 80 The top of the front wall 11 of the bag 10 extends upwardly to fit closely against and substantially flush with a front member 12 of the usual frame around the keys 13 of an Underwood typewriting machine 14. 85 The tops of side walls 15 of the bag will preferably extend rearwardly from the front wall 11 along upwardly-inclined side frame-members 16 of the keyboard frame, and then vertically along around a frame-post 17 to top side members 18 of the main frame of the machine, and rearwardly along said top side members near the rear of the machine. The tops of the side walls of the bag will preferably be arranged substantially flush with the top edges of said side frame-members on both their straight and curved portions, which may be done without interfering with the functioning of any moving parts of the machine. Arrangement of the top edges of the bag flush with the frame-members is desirable, because of the neat appearance thereby obtained. It also gives maximum contact area between the bag and the frame.

At the back corners of the machine the top of the bag offsets downwardly at 19 to pass under outwardly-extending portions 20

- of the frame that support the usual way-rod of a typewriting machine. The upper part of a back wall 21 of the bag may have a substantially level top arranged slightly 5 full, i. e., greater than the distance between the side frames, to permit easy insertion of the machine in the bag. The top line of the back wall may come to the lower edge of said way-rod-supporting portions 20.
- 10 The front wall 11 will preferably have a length equal to, or slightly less than, the front frame-member 12 adjacent the keyboard 13, so that the back may fit snugly on the key-board-frame at the front.
- 15 For more securely maintaining the bag 10 in close contact with the typewriter frame, framing pieces 22, 23 and 24 of resilient metal-like spring steel, which have the necessary stiffness, may be fastened by 20 riveting to the front and side walls of the bag and be arranged flush with the top edges thereof. The ends of the frame-strips 22, 23 and 24, as illustrated, are set back a short distance from the front corners of the bag, 25 but in certain cases the three strips may be advantageously made of one continuous piece.

Two leather strap-members 25 and 26, the first arranged with a buckle 27, and the 30 latter with holes 28, may be riveted to the rear ends of the side frame-strips 23 and 24, respectively, as illustrated in Figures 1 and 2. While the machine 14 is being lowered into the bag 10 (see Figure 3), the 35 straps will be loosened. When the tops of the frame-strips 22, 23 and 24 have come flush with the top of their associated frame-elements of the machine, the strap-members may be buckled, so as to draw the side walls 40 of the bag snugly against the frame of the machine. The straps also hold the back wall 21 closely to the back line of the machine.

As illustrated in Figures 1 and 2, the walls 45 of the bag 10 will preferably have an outward and convex bulge below the framing strips 22, 23 and 24, so that the inner surface of the walls will be held away from the metallic parts of the machine, and thereby better retard the sound-vibrations of the 50 metallic parts than if they lay against the parts. To insure that the walls of the bag bulge outwardly and not inwardly, the walls may be arranged with a small initial outward or convex bulge, as illustrated in Figure 3. Also, to this end, it may be arranged 55 for the top frame-members of the machine, as the latter is being lowered into the bag, to come flush with the top of the bag before feet 29 of the machine rest upon the bottom 60 of the bag. Then, after the strap-members 26 and 27 are buckled together for holding the bag securely to the machine frame and the machine is lowered to the bottom of the bag, the walls of the latter will bulge a 65 small amount farther out and the top of the

bag will still be held neatly flush with the several top frame-members of the machine.

In the preferred construction of the walls and bottom of the bag 10 is provided an outer layer 30, preferably made of a piece of 70 relatively thin and substantially air-tight wear-resisting material like leather or rubber. Next to the outside leather layer may be placed a relatively thick layer of sound-absorbing felt 31 followed by a layer 32 of 75 loosely-woven fabric. A second layer of sound-absorbing felt 33 may be held against the inner surface of the fabric layer. On the inner side of the second felt layer may be held a layer 34 of the same or similar 80 material as is in layer 32. The function of layer 32 is to provide dead air-space between the two felt layers. The inner layer 34, which has poor sound-reflecting properties, serves to help prevent the bag 10 from 85 acting as a kind of sounding-board. In certain cases, it may be satisfactory to construct the bag with only one layer each of felt and loosely-woven fabric.

The corners and initial outward bulge of 90 the bag 10 may be provided for by separately stretching, crimping, or molding the several layers to the desired form, before fastening them together, or the layers may be assembled flat and afterwards cut at the 95 corners and stitched or cemented.

Variations may be resorted to within the scope of the invention, and portions of the improvements may be used without others.

Having thus described my invention, I 100 claim:

1. A sound-deadening case for a typewriting machine having a keyboard frame-member, side frame-members, and way-rod supporting frame-members, including a pliable 105 open bag arranged for enclosing said machine from below up to said keyboard frame-member on the front, up to the top of the frame-members on the sides, and up to said way-rod supporting frame-members 110 on its back, said bag having relatively stiff outside frame-strips fastened along its top, front and side edges, and strap-and-buckle means at its back connecting said side frame-strips and arranged for drawing the 115 same closely against said top side frame-members, said bag being constructed of layer material having an outer layer of wear-resisting, air-tight, material and a plurality of inner layers arranged for absorbing 120 sound-vibrations.

2. An article of manufacture, including an open, pliable bag of sound-absorbing material, arranged for partially enclosing a typewriting machine from below, having a keyboard frame-member, side frame-members, and way-rod supporting frame-members, up to said keyboard frame-member on the front and up to the top of the frame-members on the sides, except where the bag 130

- offsets downwardly to pass under said way-rod supporting frame-members of the machine, said bag being provided with metallic frame-strips fastened at its top, along its 5 front and side edges, and with means in the rear of said machine for holding said side frame-strips firmly against said top side frame-members.
3. The combination with a typewriting machine, having a front keyboard frame-member and upper side frame-members extending from said keyboard frame-member rearwardly to the back of said machine, of an open, pliable bag having sound-absorbing 10 properties and arranged to enclose said machine from below up to the top side of said frame-members on its front and sides, and to a height on its back, a short distance below the highest portion of said upper side frame-members, and means arranged for holding 15 said bag closely against said frame-members, said holding means in the form of a yieldable metallic frame secured to the mouth of the bag and fitted for clasping the frame-work of the typewriting machine.
4. The combination with a typewriting machine, having a front keyboard frame-member and upper side frame-members extending from said keyboard frame-member 20 rearwardly to the back of said machine, of an open, pliable bag having sound-absorbing properties and arranged to enclose said machine from below up to the top sides of said frame-members on its front and sides, and to a height on its back, a short distance below 25 the highest portion of said upper side frame-members, and means arranged for holding said bag closely against said frame-members, said means including frame-strips fastened 30 to the outside of said bag at its top along its front and side edges, and a buckled strap fastened to the rear ends of said frame-strips and arranged to hold said bag closely against the side frame-members of said machine.
45. The combination with a typewriting machine, having a front keyboard frame-member and upper side frame-members, of an open bag having pliable, sound-absorbing walls arranged for partially enclosing said 50 machine on all sides from below and having its end and side walls arranged to extend flush with the tops of said end and side frame-members, and means for fastening the top of said walls against the top of said 55 frame-members, the side walls of said bag being arranged with initial outward bulges and initial heights greater at all points than the heights of adjoining points of said frame-members above the bottom of said machine,
- whereby said end and side walls may bulge 60 further outwardly upon fastening them to the end of the side frame-members of the machine and lowering the latter to the bottom of said bag.
6. An article of manufacture, comprising 65 an open bag of pliable, sound-proof material, arranged for enclosing a typewriting machine, having a keyboard frame-member, side frame-members and way-rod supporting frame-members, from below up to its 70 keyboard frame-member on the front, up to the top of the frame-members on the sides, and up to its way-rod supporting frame-members on the back, said bag being arranged with strap-and-buckle means for 75 holding it closely against the frame of said machine and having a back wall longer than the width of said machine, arranged to be held closely against said machine by said strap-and-buckle means. 80
7. An article of manufacture, including an open bag of pliable, sound-proof material, arranged for enclosing a typewriting machine, having keyboard frame-members and side frame-members, from below up to the 85 top of its keyboard frame-member on the front and up to the top of the top of the frame-member portions on the sides, said bag being provided with framing-strips fastened along its upper and front side edges, 90 and adjustable strap means fastened to the rear of said framing-strips, arranged for holding said bag in place on the frame of said machine. 95
8. An article of manufacture, comprising a flexible, sound-absorbing layer material for use in constructing sound-retarding bags for enclosing typewriting machines, said material having a first or outer layer of substantially thin air-tight material, a second layer 100 of sound-absorbing felt held against the inner surface of said first layer, a third layer of loosely-woven fabric held against said felt layer, a fourth layer of sound-absorbing felt held against said loosely-woven fabric layer, and a fifth inner layer of loosely-woven fabric having poor sound-reflecting qualities held against said fourth layer of felt. 105
9. An article of manufacture, comprising a flexible, sound-absorbing layer material suitable for constructing sound-retarding bags for typewriting machines, said layer of material having an outer layer of substantially air-tight, wear-resisting material and a plurality of alternating inner layers of sound-absorbing felt and loosely-woven fabric. 110

ALFRED NEWHOPE.
